UNITED STATES PATENT OFFICE

126,619

DESIGN FOR A DUAL ELECTRICAL CONNECTOR

Jean Otis Reinecke, Oak Park, Ill., assignor to
Belden Manufacturing Company, Chicago, Ill.,
a corporation of Illinois

Application January 2, 1941, Serial No. 97,770

Term of patent 14 years

To all whom it may concern:

Be it known that I, Jean Otis Reinecke, a citizen of the United States, residing at Oak Park, county of Cook, and State of Illinois, have invented a new, original, and ornamental Design for Dual Electrical Connector, of which the following is a specification, reference being had to the accompanying drawing, forming a part thereof.

Fig. 1 is a side elevational view of a dual electrical connector showing my new design;

Fig. 2 is an end elevational view of the connector;

Fig. 3 is a bottom view, and

Fig. 4 is a perspective view of the connector.

I claim:

The ornamental design for a dual electrical connector, substantially as shown.

JEAN OTIS REINECKE.
